SAFETY ATTACHMENT FOR WATERCRAFT

John H. Hermanson, Brooklyn, N. Y.

Application May 6, 1943, Serial No. 485,815

4 Claims. (Cl. 114—229)

This invention relates to safety attachments for watercraft and the same is more particularly directed to an improved means for temporarily closing a hole in the hull of ship especially when said hole results from the explosion of a torpedo striking against the hull.

Broadly, the invention comprehends the use of one or more safety units located on opposite sides of the hull of a ship and each of which units includes a closure member normally disposed in an inactive position above the water-line together with means for retaining said closure member in said inactive position and which retaining means is so constructed and arranged as to effect the automatic release of the closure member by the explosion of a torpedo in the region of said retaining means whereby said closure member will be instantly moved to an active position in covering relation to the hole in the hull for closing the same to prevent the ingress of a dangerous amount of water into the hull.

As a further feature, the invention embodies means forming a part of each safety unit for lashing down the closure member and retaining the same in covering relation to the hole in the hull to thereby preclude relative movement of the same with reference to the hull as a result of the rolling of the ship.

With the above enumerated and other objects in view, the invention is set forth in greater detail in the following specification, particularly pointed out in the appended claims and illustrated in the accompanying drawings, in which:

Fig. 1 is a fragmentary side view of a ship equipped with safety units constructed in accordance with the invention and illustrating the closure members of said units respectively in active and inactive positions.

Fig. 2 is a transverse sectional view therethrough taken approximately on the line 2—2 of Fig. 1.

Fig. 3 is a fragmentary transverse view similar to Fig. 2 illustrating as a modification a flexible roll-up type of closure member.

Fig. 4 is a similar view of a further modification showing a closure member of the sliding type.

Fig. 5 is an enlarged fragmentary view of one of the rods or poles for lashing or battening down the closure members illustrating in detail the hooked extremity thereof.

Referring to the drawings by characters of reference, A designates the hull of a ship, B the deck, C the super-structure and D the bilge keels.

As shown, the ship is provided with a plurality of safety units each of which is designated generally by the reference character E and said units are arranged on opposite sides of the hull A preferably amidships as this is the vital region and is usually the target area at which torpedoes are aimed, it being understood that the stem and stern portions are usually subdivided by bulkheads and not as vulnerable as the midships region where the engines are installed.

Each safety unit E, as disclosed in Figs. 1 and 2, includes a closure member 8 in the form of a substantially flat door or panel of size which will cover the maximum hole which is produced by a torpedo hit and said closure member is provided with a marginal packing strip or gasket 9 of rubber or any equivalent yieldable elastic material. The door or panel 8 may be constructed of any suitable material such as sheet metal, wood or any equivalent stock possessing the requisite strength to withstand the water pressure imposed thereon when in its active position in covering relation to the hole in the hull. The door or panel 8 is swingably connected to the side of the hull A above the water-line by hinge means 10, the axis of which extends horizontally and parallel with the side of the hull so that said closure member may swing downwardly and outwardly from its normal inactive position where it extends vertically upward from the hinge means 10, to its active position depending from its hinged connection with the hull. Spring means 11 is provided for urging the closure members 8 to swing outwardly and downwardly so as to insure instantaneous movement of the same to their active position in covering relation to the hole in the hull when the same are released.

In order to provide independent means for retaining the closure member 8 of each unit E in its normal inactive position against the tension of the spring means 11, which means is automatically releaseable by the explosion of a torpedo striking against the hull in the region of one or more of said safety units, an endless flexible element such as a rope or cable F is employed for each closure and said element is trained through a series of eye-bolts or screw-eyes 12 secured to the side of the hull below the closure member both immediately above and below the water-line. The flexible element is also trained around and through eyelets 13 on guide sleeves 14 disposed above the closure members and carried by the terminals of arms 15 each of which is swingably mounted on the pivot 16 of a bearing 17 secured to the deck B. The eye-bolts or

screw-eyes 12 and the sleeves 14 are so disposed that the flexible element F which is drawn taut, by adjusting the jacks hereafter described, provides a number of leads 18 extending in a substantially vertical plane parallel to and against the outwardly disposed surface of the closure member so as to retain the same in its upstanding inactive position above the water-line. This arrangement also provides a plurality of leads 19 of the flexible element F immediately above and below the water-line where one or more of said latter leads are certain to be severed by the explosion of a torpedo against the side of the hull, to thereby insure the release of the closure members 8.

For the purpose of lashing or battening down the closure members 8, when the same have been released and swung to covering relation to the hole in the hull A, each unit includes one or more flexible rods or poles 20, two being shown in the present disclosure. The rods or poles are mounted for guided longitudinal sliding movement in the sleeves 14 and normally lie in a substantially horizontal inactive position above the deck B with the outer or lower hooked extremity 21 thereof retracted to a location adjacent to the sleeve 14, the hooked extremity 21 being preferably formed as a separate section of the pole or rod and fulcrumed as at 22 within a split terminal sleeve 23 secured to the outer end portion of the rod or pole. The hooked extremity is normally urged at an angle to the pole or rod by a leaf spring 24 for a purpose which is hereinafter set forth. The inner or upper end of each pole or rod 20 is threaded as at 25 and has engaged thereon a nut 26 formed with radially projecting manipulating handles 27.

The arms 15 are adjusted and retained in various angular positions by means of jacks 28 having upper and lower threaded sections 29 and 30 which are respectively secured to the arms and deck for relative swinging movement and which jacks also include a central rotary turnbuckle section 31 for effecting relative movement of the upper section 29 toward and away from the lower section 30. The jacks are utilized for several purposes, namely, to draw the flexible element F taut, as previously set forth and to dispose the sleeves 14 in the most advantageous position when maneuvering the rods or poles 20 for effecting the lashing or battening down of the closure members 8.

Each safety unit further includes a hook 32 for each rod or pole 20 and said hooks are rotatably on vertical pins 33 adjacent to the side edges of the deck B.

In use and operation, when a torpedo strikes the side of the hull and explodes, the flexible elements F of one or more of the safety units E in the region of the torpedo hit will, as a result of the force of the explosion, be severed to thereby release one or more of the closure members 8 so that the same will instantly swing outwardly and downwardly by the combined forces of gravity and the tensioned spring means 11, thus covering the hole formed in the hull by the torpedo hit. The explosion momentarily operates to force the water away from the side of the hull so that little if any water will be shipped before the closure members 8 reach their active positions in covering relation to the hole. While the pressure of the water against the side of the hull B is sufficient to hold the closure members in covering relation to the hole, it has been found in a heavy sea that the rolling of the ship would

cause the closure members 8 to swing away from the hull and thereby uncover the hole unless some means were provided to positively retain said closures in covering relation. The rods or poles 20 have therefore been provided for this purpose and as soon as the closure members reach their covering relation to the hole, members of the crew will manually engage the hooked extremities 21 with the bilge keel D, after which the hooks 32 are engaged with the rods or poles 20. The engagement of the hooked extremities 21 with the bilge keel is greatly facilitated due to the fact that said extremities are urged at an inwardly directed angle by the leaf springs 24. After this has been accomplished and the hooks 32 engaged the rods or poles 20 will then be flexed to overlie the closure member and to coincide with the contour of the side of the hull. The nuts 26 are then tightened down against the guide sleeves 14 to draw up on the rods or poles to thereby retain the hooked extremities in fixed interengagement with the bilge keel. It will thus be evident that the rods or poles function as a means for lashing or battening down the closure members 8 against the side of the hull B in covering relation to the hole with the packing strip or gasket compressed into sealing contact with the hull and in surrounding relation to the hole.

In the form of the invention shown in Fig. 3, the safety unit embodies a flexible roll-up type of door or panel 35 with the upper end 36 thereof anchored to the side of the hull above the water-line while in Fig. 4, the safety units are provided with doors or panels 37 which are mounted on the hull for vertical guided sliding movement with reference thereto. The doors or panels in said modifications are similarly retained in their inactive positions by the flexible elements F and released in the same manner as previously described in connection with the swinging closure members 8 and are battened or lashed down by the rods or poles 20 in the manner previously set forth in connection with the closure members 8.

What is claimed is:

1. In an attachment for watercraft, safety units for closing holes formed in the hull of a ship by torpedo hits, each unit including a closure member mounted on the hull for movement from a raised inactive position above the water-line to a lowered active position in covering relation to the hole in the hull, and means for normally retaining said closure member in a raised inactive position above the water-line which includes an endless flexible element having a portion engaging with said member to hold the same in the inactive position and a portion disposed below said member in a position to be severed by the explosion of a torpedo hit in the region of the closure member.

2. In an attachment for watercraft, safety units for closing holes formed in the hull of a ship by torpedo hits, each unit including a closure member mounted on the hull for movement from a raised inactive position above the water-line to a lowered active position in covering relation to the hole in the hull, and means for normally retaining said closure member in a raised inactive position above the water-line which includes an endless flexible element having a portion engaging with said member to hold the same in the inactive position and a portion disposed below said member in a position to be severed by the explosion of a torpedo hit in the region of the closure member, said retaining means also in-

cluding a device disposed above the closure member when in its inactive position through which device the upper portion of the flexible element is trained.

3. In an attachment for watercraft, safety units for closing holes formed in the hull of a ship by torpedo hits, each unit including a closure member mounted on the hull for movement from a raised inactive position above the water-line to a lowered active position in covering relation to the hole in the hull, and means for normally retaining said closure member in a raised inactive position above the water-line which includes an endless flexible element having a portion engaging with said member to hold the same in the inactive position and a portion disposed below said member in a position to be severed by the explosion of a torpedo hit in the region of the closure member, said retaining means also including adjustably swingable arms and a guide sleeve carried thereby normally disposed above the closure member when in its active position, said guide sleeve having an eyelet through which the upper portion of the endless flexible element is trained.

4. In an attachment for watercraft, safety units for closing holes formed in the hull of a ship

by torpedo hits, each unit including a closure member mounted on the hull for movement from a raised inactive position above the water-line to a lowered active position in covering relation to the hole in the hull, and means for normally retaining said closure member in a raised inactive position above the water-line which includes an endless flexible element having a portion engaging with said member to hold the same in the inactive position and a portion disposed below said member in a position to be severed by the explosion of a torpedo hit in the region of the closure member, said retaining means also including adjustably swingable arms, a guide sleeve carried thereby normally disposed above the closure member when in its inactive position, said guide sleeve having an eyelet through which the upper portion of the endless flexible element is trained and a flexible rod having a threaded upper end slidably mounted in the guide sleeve and having a hooked lower terminal adapted to engage with the bilge keel and a nut on the threaded upper end of the rod adapted to engage with the guide sleeve for drawing the rod upwardly to batten down the closure member.
